UNITED STATES PATENT OFFICE.

CARL A. CARLSTROM, OF NEW YORK, N. Y., ASSIGNOR, BY MESNE ASSIGNMENTS, TO AUTOMATIC PENCIL VENDING MACHINE CORPORATION, OF HOUSTON, TEXAS, A CORPORATION OF DELAWARE.

VENDING MACHINE FOR PENCILS AND THE LIKE.

Application filed August 19, 1925. Serial No. 51,185.

This invention relates to a vending machine primarily adapted for use in connection with pencils although its principles may obviously be applied to vending machines or 5 the equivalent generally.

It is aimed to provide a novel construction for operation through the turning of a crank or shaft upon deposit of a proper coin in order to operate the parts and release the 10 pencil or commodity.

Another object is to provide a construction employing relatively movable, coacting elements in combination with a coin to deposit the latter within the collecting box of 15 the machine and to thereafter release the pencil.

Another object is to provide a novel means whereby the pencils may be agitated as each 20 vending operation occurs, in order to insure straight feeding of the pencils or alinement while within the machine.

Another object is to provide a novel construction wherein an endless advertising element is employed in connection with a motor, the latter being adapted to operate a 25 pencil sharpener, and controlled so as to operate only when a pencil is in engagement with the sharpener.

The specific objects and advantages will 30 become more apparent from a consideration of the description following taken in connection with accompanying drawings illustrating an operative embodiment.

In said drawings:

Figure 1 is a view of the machine in front elevation;

Figure 2 is a side elevation;

Figure 3 is a vertical sectional view taken on the line 3—3 of Figure 1 and looking toward the coin controlled parts of the machine;

Fig. 4 is a vertical sectional view taken on the line 4—4 of Figure 1;

Figure 5 is a longitudinal sectional view taken on the line 5—5 of Figure 2;

Figure 6 is a detail sectional view taken on line 6—6 of Figure 1 with an operating coin in initial position, and

Figures 7 and 8 are views similar to Figure 6 showing the parts in different stages of operation.

Referring specifically to the drawings, a suitable type of casing is provided as generally designated A, which for instance, may be rectangular in cross section as shown 55 employing a bottom or base wall 10, a back or rear wall 11, side walls 12, a front wall 13 and a top wall 14. In order that the casing may be opened, walls 13 and 14 are hinged in place at 10^a and may be conveniently normally locked together at 11^a.

Arranged within the casing are two spaced uprights 16 and 17, the former being preferably arranged adjacent one of the walls 12. Spanning the uprights 16 and 17 65 are side walls 18 and 19, which are fastened to the walls 16 and 17 in any suitable manner as by the passage of lugs 20 thereon through openings in the walls 16 and 17 and subsequent clinching thereof. Wall 19 has 70 an integral downwardly and inwardly inclined bottom portion at 21. At the lower portion of the wall 18, a bottom wall 22 is provided, however being pivotally connected as at 23 on a suitable rod 23^a mounted in 75 the walls 16 and 17. The parts just described constitute a hopper generally designated H which is usually of a size to hold a gross of pencils P or desired quantity of any commodity but which obviously may be 80 of any size preferred. The pencils or commodity may be viewed through a window 13^a in wall 13. Walls 21 and 22 have an outlet passage 24 between them which is defined by depending walls or flanges 25 and 85 26, respectively integral with them. The pencils P are adapted to be vended or discharged one at a time through the deposit of a coin as suggested at 27 (Figs. 6 to 8) through a slot 28 in the front wall 13 and 90 passage-way 28^a within the machine the pencils traveling down a guide plate 29 preferably inclined as shown, through an opening 30 in the wall 13 and onto a supporting rack or element 31 disposed exteriorly of the machine so that the pencil may be manually 95 removed.

The coin 27 upon reaching the interior of the machine abuts the forward end 32 of a lever 33. Lever 33 is pivoted at 34 to wall 100 17 and is urged upwardly at the coin end by a contractile spring 35 secured thereto and

to wall 17, the upward movement of such lever being limited by a suitable stop 33^a on wall 17.

A filler 27^a if necessary may be fitted to the inner surface of wall 13 in passageway 28^a so that the coin will be held by same and lever 33 until the machine is operated and to form an operating connector.

A rock shaft 36 is journaled in wall 17 and has a crank 37 thereon which has a pin and enlarged slot connection as at 38 with the lever 33 so that as the lever 33 is operated, the crank 37 will turn the shaft 36 one quarter of a revolution. Shaft 36 has spaced retainers 39 thereon between which a pencil P is adapted to be received for discharge to the end that through the one quarter revolution before referred to, the pencil will be discharged onto the guide 29.

20 Retainers 39 normally abut the lower edges of flanges 25 and 26 (Fig. 4).

Each retainer 39 has a cam 40 of such shape that it is normally in direct supporting engagement with the lower end of wall 26 at cutaway portions 26^a and as the shaft 36 is rocked forwardly on its one quarter revolution heretofore referred to, said cams will tilt the wall 22 so as to insure alinement of the remaining pencils with the passageway 24, and will also extend under the pencils next to be discharged so as to prevent discharge until the shaft 36 returns to normal position and likewise the retainers 39 return to normal position and engage the remaining pencils.

The machine has an operating shaft 41 journaled for rocking in the wall 17 and adjacent wall 12. Said shaft 41 has a manipulating crank 42 extending to the exterior of the machine and said crank has a guard and ejector element or plate 43 rigid therewith. Plate 43 has a projection 42^a which normally is opposite a shoulder 34^a on lever 33, being urged to that position by 45 a contractile spring 44 connected to the plate 17 and to the crank 42, so that the lever 33 cannot be accidentally actuated.

In operation, say a coin of predetermined size or value is deposited in the slot 28 by the purchaser, it will engage filler 27^a and the nose or shoulder 32 of lever 33 as in Figure 6. The coin thus forms an operating connector and the purchaser then depresses crank 42, rocking shaft 41. As a result, and as shown in Figure 7, projection 42^a is moved away from shoulder 34^a and the plate or ejector 43 engages the coin and depresses it past the lever 33, the lever 33 swinging on its pivot 34 to accommodate such movement, and the coin then falls into a removable collection box or tray 45. The movement of lever 33 is imparted to crank 37 which rocks shaft 36 forwardly and causes the retainers 39 to discharge the engaged pencil P onto the guide 29 so that it may roll ex-

teriorly of the machine and into engagement with the rack 31 for manual removal by the purchaser. As the shaft 36 rocks, the cams 40 tilt the wall 22 to agitate the pencils to maintain them in proper alinement and engage under the lowest pencil remaining in the machine or passageway 24 so as to prevent premature discharge thereof before deposit of the proper coin by the next purchaser. The springs 35 and 44 return the parts to normal position after operation.

Plate 43 performs a further function in that in operation it guards passageway 28^a against more than one coin being received at a time, since it will eject a second coin as suggested in Figure 8.

It will be noted that considerable space is provided within the casing not occupied by the mechanism referred to and therein supported on the base 10 is a suitable electric motor M, deriving its current from any suitable source. To one end of the main shaft 46 of said motor M, a pencil sharpener 47 is secured and the purchased pencils may engage the pencil P sharpener by insertion through an opening 48 (Fig. 1) in the front wall 13 of the casing. The motor M is normally idle. Its circuit includes two contacts 49 and 50 so arranged that as the pencil passes through the opening 48 it engages contact 49 which is of jack-knife blade form and moves it into engagement with contact 50, thus establishing the electric circuit through the motor and maintaining such circuit established until the pencil is removed, whereupon the spring of contact 49 will move it out of engagement with contact 50.

Within the machine at one side thereof in a space S, a suitable flexible endless tape 51 is provided which has suitable advertising or other data delineated thereon adapted to be displayed through a window or opening 52 in the wall 13 opposite the space S. This tape passes over suitably journaled guide rods or pins 53 and over two sprocket wheels 54 which are keyed to the shaft 36. The sprocket wheels 54 have their teeth 54^a in mesh with slots 55 provided adjacent the borders of the tape 51. By this sprocket connection with the shaft 36, the tape will be driven a limited distance, each time the machine is operated and through such operation. The sprocket wheels 54 are loose on shaft 36 and have pawls 56 engaging ratchets 57 on shaft 36 so that the wheels 54 will properly coact with said shaft by turning in one direction only and slipping when the shaft is turned in the opposite direction to avoid injury to the tape by retrograde movement of said shaft.

Various changes may be resorted to provided they fall within the spirit and scope of the invention.

What is claimed is:—

1. A vending machine having a lever

adapted to receive a coin thereagainst, article-discharging means operable through movement of the lever, an ejector engageable with the coin to shift the lever and deposit the coin in the machine, said ejector having a portion normally opposite the lever and preventing actuation thereof by a coin.

2. A machine of the class described having

a rock shaft, means on said shaft engageable with the article to be vended to discharge the same, a crank on said shaft, a lever engaging said crank and arranged for deposit of a coin against the same, and means operable to move the coin to operate the lever.

In testimony whereof I affix my signature.

CARL A. CARLSTROM
